UNITED STATES PATENT OFFICE.

ANDREW J. TICE, OF CANTON, OHIO, ASSIGNOR TO THE UNITED ELECTRIC COMPANY,
OF CANTON, OHIO, A CORPORATION OF OHIO.

SUCTION CLEANING-NOZZLE.

1,161,908.

Specification of Letters Patent. Patented Nov. 30, 1915.

Application filed February 13, 1912. Serial No. 677,318.

To all whom it may concern:

Be it known that I, ANDREW J. TICE, a citizen of the United States, residing at Canton, in the county of Stark and State of Ohio, have invented certain new and useful Improvements in Suction Cleaning-Nozzles, of which the following is a specification.

The invention relates to suction nozzles for vacuum cleaning machines, and pertains more particularly to that class of nozzles having a long narrow slot in the normal lower side, the lips of which slot are usually formed in the same plane, and are adapted to be presented to or abutted against the carpet, floor or other objective surface to be cleaned.

The objects of the improvement are to provide a swivel joint between the nozzle and its tubular handle, whereby a straight handle may be used which can be rotated into planes either parallel with or oblique to the lip plane without tilting or removing the nozzle lips from the objective surface, at the same time turning the nozzle at different angles with respect to the axis of the handle in the intermediate positions of its inclination to the lip plane.

Further objects of the improvement are to provide such a swivel joint between the nozzle and its handle as will be practically operative without binding or being cut by grit or dust from the nozzle, which can be simply made without any protruding or intruding parts, and which can be conveniently assembled.

The general objects of the improvement thus set forth, and other ancillary advantages, are attained by the preferred embodiment of the invention, illustrated with two different forms of nozzle, in the accompanying drawings, forming part hereof, in which—

Figure 1 is a plan view of one form of nozzle with part of the handle showing the improved joint, the handle being inclined obliquely upward from the cleaning plane, and the length of the nozzle being located at right angles to the axis of the handle; Fig. 2, a similar view showing the length of the nozzle turned obliquely to the axis of the handle, in one direction by full lines, and, in the opposite direction, by broken lines; Fig. 3, an axial section on line 3—3, Fig. 1; Fig. 4, a similar section of the nozzle with detached side elevations of the handle and screw plug

in position for assembling; Fig. 5, a plan view of a modified form of nozzle with part of the handle, showing the nozzle at right angles to the axis of the handle in full lines, and, obliquely inclined thereto, in broken lines; and Fig. 6, an axial section on line 6—6, Fig. 5, showing the handle rotated with its axis parallel to the cleaning plane in full lines, and inclined obliquely thereto, in broken lines.

Similar numerals refer to similar parts throughout the drawings.

The nozzle 1, in the form illustrated in Figs. 1 to 4, is made hollow in the usual manner with an elongated narrow slot 2 in the normal lower side, the lips 3 of which slot are located in the same plane and are adapted to be presented against a carpet, floor or other objective surface 4, from which lips the walls 5 of the nozzle diverge from the sides and converge from the ends to form the central tubular stem 6 directed upward and rearward and having the plane of its open end 7 located oblique to the lip plane.

Within the end portion of the tubular stem 6 is formed the cylindric socket or journal bearing 8 having the annular race-way 9 therein with an aperture 10 in one side adapted to be closed by the screw plug 11, which plug is preferably turned home in the aperture when the race-way is being milled, so that the inner end 12 of the plug is properly shaped to form part of the race-way. It will be understood that the cylindric socket 8 and the race-way 9 are formed co-axial with the end 7 of the head and are likewise located oblique to the lip plane.

The end 13 of the tubular handle 14 is obliquely beveled, preferably to the same angle from the handle axis as the axis of the bearing socket 8 is inclined from the lip plane; and on this end of the handle, which is formed co-axial with the main portion thereof, is formed the journal 15 adapted to neatly fit the nozzle socket 8, which journal is provided with the annular packing groove 16 adjacent to the end, and the annular race-way 17 inside the packing groove, which parts are all made co-axial with the beveled end of the handle.

For assembling the parts to form the swivel joint, a suitable packing ring 18, preferably of fibrous material, is placed in the packing groove, the handle journal is

- telescoped in the nozzle socket until the race-ways register, after which the bearing balls 19 are inserted through the aperture 10, and the screw plug 11 is inserted to complete the joint. It is evident that the swivel joint thus formed has no objectionable protruding or intruding parts; that the bearing balls are protected from dust and grit by the packing ring 18; and that the bearing balls 10 rotatably engage the parts together without the use of any clamping means, adjustable or otherwise, and that, by removing the balls, the handle and nozzle may be freely disengaged.
15. In the modified form of nozzle 1^a illustrated in Figs. 5 and 6, the end sections 20 are conically shaped with the smaller ends outward and having the inner larger or base ends connected by the cylindric body section 20 21, from which body section the tubular stem 6^a extends directly rearward, parallel with the lip plane, the end 7^a of the tubular stem being located oblique to the cleaning plane. Within the end portion of the stem 6^a is formed the cylindric socket or journal bearing 8^a having the annular race-way 9^a with the aperture 10^a normally closed by the plug 11^a; in which socket is engaged the oblique journal 15 on the end of the straight handle 14 by means of the bearing balls 19, just the same as described for the form of nozzle illustrated in Figs. 1 to 4.
30. In the use of the nozzle, it is evident that the handle may be rotated from an upwardly inclined position at right angles to the lengthwise axis of the nozzle, as shown by full lines in Figs. 1, 3 and 5, and, by broken lines, in Fig. 6, to a position parallel with the lip plane and also at right angles to the lengthwise axis of the nozzle, as shown by broken lines in Figs. 3 and 5, and, by full

lines, in Fig. 6, which latter figure shows quite plainly that the nozzle can be inserted under any overhanging obstacle, as an article of furniture, which is not lower than the height of the nozzle itself. Furthermore, it is evident that, by rotating the handle from its highest inclined position to its prone position, the nozzle will be deflected to an angle either on one side or the other from the axis of the straight handle; all of which can be done without tilting or removing the lips of the nozzle from the objective surface.

I claim:

1. A suction cleaning nozzle having a long narrow slot with coplanar lips and having a tubular stem with a cylindric socket in its end oblique to the lip plane, and a straight tubular handle having an oblique journal on its end rotatably engaged in the socket.
2. A suction cleaning nozzle having a long narrow slot with coplanar lips in its lower side and having a rearwardly extending tubular stem with a cylindric socket in its end oblique to the lip plane, and a straight tubular handle having an oblique journal on its forward end rotatably engaged in the socket.
3. A suction cleaning nozzle having a long narrow slot with coplanar lips and having a tubular stem, and a straight tubular handle, there being a cylindric socket in the end of the one tubular member and a journal on the end of the other tubular member rotatably engaged in the socket, the axis of the swivel joint thus formed being oblique to the lip plane and to the axis of the handle.

ANDREW J. TICE.
